UNITED STATES PATENT OFFICE.

ROBERT R. HUGHES, JR., OF NYACK, NEW YORK, ASSIGNOR TO LUCIUS N. LITTAUER, OF GLOVERSVILLE, NEW YORK.

SEWING-MACHINE.

1,232,315.

Specification of Letters Patent.

Patented July 3, 1917.

Application filed April 21, 1914. Serial No. 833,355.

To all whom it may concern:

Be it known that I, ROBERT R. HUGHES, Jr., a citizen of the United States, residing at Nyack, in the county of Rockland and State of New York, have invented certain new and useful Improvements in Sewing-Machines, of which the following is a specification.

This invention relates to sewing machines, and more particularly to improved means for making a triple seam, the object of the invention being to provide means for trimming simultaneously the edges of several pieces or plies of work and folding the same, and then infolding such edges thereby to provide a triple seam made up of six plies of material, and to do this expeditiously and by a comparatively simple mechanism readily accessible to the operator and one which is not liable to get out of order.

In working up material of various colors it is frequently very difficult, if not at times impossible, to obtain a binding which will properly or exactly match the color of the goods, but by means of the present improvement the necessity of binding the edge is entirely avoided, while the cost of production is decreased.

I am aware that it is not new to fold one edge of a piece of material for the purpose of sewing it to the raw edge of another piece thereof, or even to fold both edges of such pieces for the purpose of sewing them together, but the present improvement has to do particularly with an improved mechanism for obtaining a triple seam.

Therefore it is the object of the present improvement not only to provide mechanism which will produce a seam of the character described, but to provide means all co-operating in such manner that the work to be done thereby will be efficiently performed, and furthermore, to provide a mechanism in which all of the operating parts will be located in front of the needle and to also provide a mechanism in which the several parts will co-operate with the presser foot, and in which also the several parts will so co-operate that the necessity of feeding one layer or ply of material spaced apart from another layer or ply of material is avoided, so that the several layers of material may be fed under the presser foot in the usual

manner, that is one on top of and in engagement with another, whereby the proper feeding of the several layers of material will simultaneously take place.

In the drawings accompanying and forming part of this specification, Figure 1 is a front view of a portion of a sewing machine illustrating the present improvement applied thereto; Fig. 2 is a plan, partly sectional, view of the present improvement; Fig. 3 is an end view of so much of the machine as is shown in Fig. 1, looking from left to right; Fig. 4 is a cross-sectional view taken in line 4-4, Fig. 1, and looking toward the left; Fig. 5 is a detail view of the throat plate; Fig. 6 is a detail view of the feed dogs; Fig. 7 is a perspective view of the infolder; Figs. 8 and 9 are detail views illustrating the operation of such infolder and the parts co-operating therewith; Figs. 10 and 11 illustrate the manner in which the folded edges of the several plies of material are infolded by the infolder shown in Figs. 8 and 9; Fig. 12 is a detail top view of a part of the mechanism shown in Figs. 8 and 9; Fig. 13 is a detail view of the gripper or clamp; Fig. 14 is a top view illustrating the manner in which the material is cut and folded, the said view illustrating some of the parts co-operating with the presser foot; Fig. 15 is another detail view of the means hereinafter designated as the gripper for holding the work in position for the action of the infolder; Fig. 16 is a perspective view of the presser foot; and Figs. 17, 18 and 19 are detail views of the improved top feed mechanism hereinafter referred to.

Similar characters of reference indicate corresponding parts in the different figures of the drawings.

In the present improvement the several plies of material, two or more, two being shown herein, are first fed under the presser foot, whereupon the edges thereof are trimmed and such trimmed edges are then folded together and the so folded edges then held and also to a certain extent pushed in position for the action of the infolder, which then engages the same and infolds the trimmed edges upon themselves, at the same time assisting in feeding the folded material toward the needle, whereupon the needle penetrates the triple fold, thus pro-

viding a triple seam and making it unnecessary to bind the same with an independent binding.

It will of course be understood that this improved infolding means may be used with one layer of material or with two or more layers, as occasion may require. The present invention is in part an improvement upon my prior Patent No. 1,075,422, dated 10 October 14th, 1913, and while in some respects the principle of operation of certain of the parts is similar the several devices operate in a somewhat different manner.

In the present improvement a somewhat different form of means for forming the first fold is provided, in that in the present case a bracket is secured to the trimmer stand, having an upturned slightly curved guiding device for guiding the material to the trimmer, which in the present instance likewise operates in a somewhat different manner from that shown in my prior case, in that the movable blade of the trimmer is horizontally supported for movement in a horizontal path against the fixed blade of the trimmer, and carried by this trimmer is a curved guard, which is effective to deflect the trimmings out of the path of the needle. Underneath this guard and the movable blade of the trimmer is a rocking member oscillating in a vertical path and comprising a pair of arms or parts 86 and 87 one of which is effective to fold and the other of which is effective to clamp the so folded material within the chamber of the presser foot prior to the same being infolded by the infolding foot which infolding foot operates in much the same manner as in my prior case although somewhat differently formed 40 and supported.

In addition to the foregoing means, I use in combination therewith a four-motion top feed connected with the main shaft and movable in the line of the work with the infolding means by reason of its being connected to the feed bar and reciprocating back and forth with the infolding means in the line of the work. This top feed is provided with a telescopic connection having a yielding spring chamber which permits the feed to automatically adjust itself to various thicknesses of seams.

In the present embodiment of the improvement so much of a sewing machine only is shown as is necessary to illustrate this improvement, and this comprises the usual base portion 2 including a cloth or bed plate 3, the usual driving mechanism, an overhanging arm or gooseneck 5, a part only 55 of which is shown, terminating in a head 5', a needle actuating lever 6, a part only of which is shown, pivoted to the overhanging arm for reciprocating the needle bar 7 in the usual manner, and a presser foot bar 8 60 supported in the usual manner for carrying

at its lower end a detachable presser foot 9, which in the present instance is somewhat differently constructed from the ordinary presser foot and the construction of which is more clearly illustrated in Fig. 16. Located under this presser foot are the usual feed dogs 10 for feeding the material to the needle. 70

The forward or projecting portion of the presser foot is upwardly bent to form a recess, as 11, and in this recess is located the fixed blade 12 (see Fig. 2) and the movable horizontally working blade 13 of the trimming mechanism, the movable blade being reciprocated in a horizontal path by suitable connecting means operated from the main driving shaft. 75

The trimming bracket 14 is secured to the base 2 as at 15. The bracket 14 has a vertical portion 16 terminating in an overhanging portion 17 provided with a bearing to receive one end of the vertical shaft 18, while the lower end of the shaft has a bearing in the portion 14 supporting the knife lever 19 for axial movement. A curved upwardly extending portion 20 of the lever 19 receives the movable knife 13 and operates in a horizontal path to and fro past the needle line from right to left. An arm 21 of the lever 19 is connected to the main driving shaft by means of a ball and socket joint 22 and a rod 23 by means of an eccentric strap 24 mounted on an eccentric 25, which is secured to the main shaft 26 to reciprocate and give the proper cutting movements to the trimmer blade 13. The stationary blade 12 is clamped to the portion 17 of the trimmer bracket indicated at 27, see Figs. 1 and 4. 80

A U-shaped clamp 28 secures the stationary knife in such position that the cutting edge 29 (see Fig. 2) thereof extends into the recess 11 of the presser foot substantially in line with the needle. The tension of one knife relatively to the other for 100 the purpose of adjusting the cutting action is accomplished by means of an adjustable bushing 30 which is tapped into the overhanging portion 17 of the bracket 14 so as to force the lever 19 downward, thus bringing the movable knife 13 into proper contact with the knife 12 to produce a keen cut. 105

The object of having the knives trim horizontally, instead of vertically as in my said patent hereinbefore referred to, is to assist 120 the fold manipulators in forming the seam, as it will be obvious that the initial fold takes place as the material reaches the cutting members, and the margin of material to be turned in making the seam is determined by the distance the cutters are spaced from the top surface of the cloth plate 3. 125

Secured to the vertical portion 16 of the bracket 14, as at 31, is a plate 32 provided with a former 33, which is shaped so as to 130

assist in guiding the work into the machine, said former having an upturned overhanging portion 34 which serves to fold over the material as shown in Fig. 14, so that the trimmed edge of the material is directed to the left of the needle as distinguished from the practice heretofore of having the trimmings pass to the right of the needle. A suitable guide piece 35 is so shaped and positioned relatively to the knife 13 as to catch and deflect the trimmed portion out of the path of the needle, see Figs. 1, 2 and 4, it being understood, of course, that the shape of these formers and guides may be varied to suit the character of material being operated upon, the particular outline or shape not being essential so long as these devices serve the purpose of holding the goods vertically as it enters the trimmer and deflect the trimmed margin away from the needle.

The presser foot is recessed, as at 37, to provide a working space for the gripper and infolder to pass the material around the spring tongue 38, which is so shaped as to 25 have its end extending in near the needle and bent downward to lie on the wall of the presser foot, as at 39, so as to hold the seam after it has been formed. The needle operates in a cut-out at 40, while the top feeding member operates behind the needle close to the wall 41 of the presser foot. The feed dog 10 is provided with a suitable toothed surface and is so shaped as to operate close to the trimmer at the front and provided 35 with an upwardly extending heel 42; which prevents the seam from moving laterally away from the needle-line as the gripper and infolder are acting upon the work. The cut-out 43 is for the passage of the looper forming part of the stitch mechanism. A detailed description of this, however, is deemed unnecessary as it forms no part of this invention. It is obvious that this improved folding and trimming mechanism to form a 45 triple seam may be applied to any of the well known stitching machines.

The feeding mechanism is of the well known four-motion variety. The feed dog 10 operates through the slots 44 of the throat plate 45, see Fig. 5. A guard 46 is secured to the end of the plate to direct the seam of the material passing through the machine from the moving parts so that it will be delivered in clean condition. The needle reciprocates through the usual needle hole 47 in the formation of the stitch. Secured to the presser foot bar 8, as at 48, is one end of the bracket 49, which operates in a slot 50 of the machine head 5 and is guided therein 55 for vertical movement with the presser foot and bar.

At 51, see Figs. 4 and 17, is secured the mechanism of the infolding and clamping members. A bracket 52 is provided with a bearing 53 for the shaft 54, the other end

being provided with a bearing 55 for the shaft 54 adjacent the needle. This bearing extends downwardly, terminating in another bearing 56 for the rock shaft 57, which carries the gripper 58, the other end of the shaft 57 being provided with a collar 59.

From the foregoing it will be seen that both shafts 54 and 57 have the same vertical movements as the presser foot or presser bar, being connected therewith. The shaft 54 is 75 reduced, as at 60, affording a shoulder 61 for the block 62. A sleeve 63 affords another shoulder for the block 62, while the nut and lock-nut 64 is provided for adjusting these parts so that the shaft 54 will have free rotary movement in the block 62 and be reciprocated in the direction of its length to the same extent as the feed dog 10, by means of a link 65 connected to the block 62 at one end and to a bracket 66 secured to the feed bar 67. The gripper 58 is as hereinbefore stated, formed with two arms, and is connected as at 68, with the rod 69 for movement therewith. The rod 69 is provided with an adjusting means 70 to regulate its 80 length, and terminates in a telescopic connection, as 71 (see Fig. 2), having a compression spring located therein to cushion the gripping action on the material and compensate for variation in thicknesses. 85 This connection 71 is bifurcated, as at 72, to receive one end of a bell crank lever 73 pivoted as at 74 in a bracket 75, the other arm 76 of the lever being connected to a link 77 which is actuated by the joint 78 100 pivotally secured as at 79 to the needle lever 6 (see Fig. 1). A ball and socket 80 is also secured to the needle lever, and a reciprocating rod 81 having a ball and socket 82 connected to the arm 83 of the infolder 84 105 is secured to the shaft 54. The work-engaging end 85 of the infolder is so shaped as to operate within the recess 37 and pass underneath the end of the spring tongue 38 to project the cut edge of the material to 110 the right of the needle, and to turn the edge of the material around the portion 39 of the tongue. The gripper 58 also works in the said recess and by reason of its recessed portion 86 acts to further fold the edge into 115 an overlapping position on the material, that is, give it a half fold and then properly hold such folded edge for the action of the infolder, while its heel 88 prevents the material from bulging or moving laterally. 120 This heel cooperates with the heel 42, which is attached to the feed dog 10 in such a manner as to control the size and width of the seam. Secured to the presser bar, as at 89, see Fig. 3, is a yoke 90, which clamps the guide bar 91 so that it has the same vertical movement as the presser bar 8, and secured to the end of this bar 91 is a bracket 92 which extends upward and outward and is so shaped as to straddle the presser bar 130

and be guided thereby. Pivotally secured to the block or bracket 92 is a link 98 having a top feed foot pivotally secured to its lower end, as at 94. This feed foot is pivotally connected, as at 95, to a vertical extension 96 of the bracket 66 carried by the feed bar 67. The feed foot 97 is provided with the usual toothed surface 98 and is so shaped as to operate close to the heel 41 of the presser foot 9 and acts upon a portion of the main feed dog 10 to grip the folded seam and feed it through the machine at a uniform speed irrespective of the character of material.

15 One of the difficulties heretofore present with machines of this character was to prevent the puckering of the seam on certain classes of material, while on others the seam would stretch, which was caused by the 20 seam having six thicknesses of material along the needle line and only two thicknesses under the remaining portion of the foot. This disadvantage is entirely obviated by the use of this improved mechanism.

From the foregoing it will be obvious that, in addition to the movements provided for folding the material to form the triple seam, first, bending it over, second, turning it outward, third, turning it under, I have so organized the several parts that certain of them, including the gripper, infolder, top feed, act upon the seam of the material, to move in unison with the feed dog 10 to 35 advance the material positively and uniformly past the stitching mechanism.

To compensate for variations in thickness of the seam and to regulate the tension of the top feed 97 upon the work, and to give 40 it a positive lifting and gripping motion, I have provided an eccentric 99 secured to the main shaft 26 and operating a connection 100, which is provided with a telescopic tension device 101 terminating in a ball and 45 socket joint 102, which is secured to the block 92 secured to the bar 91. Through the mechanism just described a lifting motion is given to the top feed at the time the bottom feed is moving away from the work, the 50 two being so timed as to clamp the seam during a portion of each rotation of the main shaft.

The operation of the machine is as follows: The material is guided to the machine underneath the presser foot so that the former 38 and 34 turns the edges upward, that is, gives it substantially a quarter turn or fold and permits the trimmer to remove the ragged edges. The feed grips the work 55 and moves it inward, while the gripper grips the work upon the tongue 39 in the recess 37 of the presser foot. While the needle is descending, each time the work engaging end 85 of the infolder operates to

push the edge of the material underneath 65 the tongue 39 the feed rises and moves backward, carrying with it the gripper and infolder while they are acting upon the seam. At the same time the top feed 97 is gripping the seam between it and the feed dog 10 so as to advance the material positively. When the feed dog 10 disengages the top feed 97 also rises away from the work, while the infolder 85 and the gripper 58 are so timed as to release the work while it advances to receive the next stitch. The trimmer is timed so as to sever the edges while the work remains clamped between the foot and throat plate in substantially a stationary position.

80 In my prior patent as well as in the present improvement a triple seam is obtained, but in the present improvement this triple seam is obtained by a more gradual folding of the edge of the material, one advantage of which permits the use of the horizontal knife hereinbefore referred to and the trimming of the material after the first fold. In my prior patent the edge was first trimmed and then such edge completely folded over 90 upon itself, whereas in the present instance the edge of the material is but partially folded, that is, folded substantially a quarter turn, or upward as hereinbefore stated, and then trimmed and then further completely folded upon the goods. During this 95 second folding the edge is folded laterally and also depressed, while at the same time the so folded edge is clamped for the infolder, such lateral folding and depression 100 of the edge as well as the clamping being accomplished by a single means.

I claim as my invention:

1. In a sewing machine, the combination of means for folding the edge of the work, a single means for further folding such edge laterally and depressing it and also clamping the so folded edge, and means for then infolding the said folded edge.

2. In a sewing machine, the combination 110 of means for folding the edge of the work, a single means for further folding such edge laterally and depressing it and also clamping the so folded edge, and means for then infolding the said folded edge and comprising means movable transversely of the line of travel of the work.

3. In a sewing machine, the combination of means for folding the edge of the work upwardly substantially a quarter turn, a 120 single means for further folding such edge laterally and depressing it and also clamping the so folded edge, and means for then infolding the said folded edge and comprising means movable transversely of the line 125 of travel of the work and also movable with the work.

4. In a sewing machine, the combination

of means for folding one or more plies of material, means for infolding the so folded edges and comprising means movable transversely of the line of travel of the material, and trimming means having a movable blade movable in a horizontal path.

5. In a sewing machine, the combination of means for folding the edge or edges of one or more plies of material, means for infolding the so folded edges and comprising means movable transversely of the line of travel of the material and also movable with the work, and trimming mechanism having a movable blade movable in a horizontal path.

15. 6. In a sewing machine, the combination of means for folding the edge or edges of one or more plies of material, means for infolding the so folded edges and comprising means movable transversely of the line of travel of the material and also movable with the work, trimming mechanism having a movable blade movable in a horizontal path, and means for automatically moving the movable blade of the trimming mechanism and said infolding means.

7. In a sewing machine, the combination of means for folding the edge or edges of one or more plies of material, means for folding the so folded edge, independent automatically operative means for then infolding the so folded edge, and a top feed automatically adjustable to varying thicknesses of seams.

35. 8. In a sewing machine, the combination of means for folding the edge or edges of one or more plies of material, means for folding the so folded edge, independent automatically operative means for then infolding the so folded edge, a top feed automatically adjustable to varying thicknesses of seams, and means for moving the infolding means transversely of the line of travel of the material.

45. 9. In a sewing machine, the combination of means for folding the edge or edges of one or more plies of material, means for folding the so folded edge, independent automatically operative means for then infolding the so folded edge, a top feed automatically adjustable to varying thicknesses of seams, means for moving the infolding means transversely of the line of travel of the material, and means for moving said infolding means with the work.

60. 10. In a sewing machine, the combination of means for folding the edge or edges of one or more plies of material, means for folding the so folded edge, independent automatically operative means for then infolding the so folded edge, a top feed automatically adjustable to varying thicknesses of seams, means for moving the infolding means transversely of the line of travel of the material,

and trimming mechanism for trimming the material prior to the folding of the work.

11. In a sewing machine, the combination of means for folding the edge or edges of one or more plies of material, independent automatically operative means for infolding the so folded edge, a top feed automatically adjustable to varying thicknesses of seams, means for moving the infolding means transversely of the line of travel of the material, means for moving said infolding means with the work, and trimming mechanism for trimming the material prior to the folding of the work.

12. In a sewing machine, the combination of means for folding the edge or edges of one or more plies of material, independent automatically operative means for infolding the so folded edge, a top feed automatically adjustable to varying thicknesses of seams, means for moving the infolding means transversely of the line of travel of the material, and trimming mechanism for trimming the material prior to the folding of the work, said trimming mechanism including a fixed blade and a horizontally movable blade.

13. In a sewing machine, the combination of means for folding the edge or edges of one or more plies of material, independent automatically operative means for infolding the so folded edge, a top feed automatically adjustable to varying thicknesses of seams, means for moving the infolding means transversely of the line of travel of the material, means for moving said infolding means with the work, and trimming mechanism for trimming the material prior to the folding of the work, said trimming mechanism including a fixed blade and a horizontally movable blade.

14. In a sewing machine, the combination of means for folding the edge of one or more plies of material and comprising oscillatory means movable in a vertical path, means for infolding the previously folded edge and comprising means likewise movable in a vertical path, and means for automatically moving said two means.

15. In a sewing machine, the combination of means for folding the edge of one or more plies of material and comprising oscillatory means movable in a vertical path, means for infolding the previously folded edge and comprising means likewise movable in a vertical path, and means for automatically moving said two means, said infolding means movable transversely of the work and also in the line of travel of the work.

16. In a sewing machine, the combination of means for folding the edge of one or more plies of material and comprising oscillatory means movable in a vertical path, means for infolding the previously folded

edge and comprising means likewise movable in a vertical path, means for automatically moving said two means, and trimming mechanism having a movable blade movable in a horizontal path.

17. In a sewing machine, the combination of means for folding the edge of one or more plies of material and comprising oscillatory means movable in a vertical path, means for infolding the previously folded edge and comprising means likewise movable in a vertical path, means for automatically moving said two means, said infolding means movable transversely of the work and also in the line of travel of the work, and trimming mechanism having a movable blade movable in a horizontal path.

18. In a sewing machine, the combination of means for folding the edge of one or more plies of material and comprising oscillatory means movable in a vertical path, means for infolding the previously folded edge and comprising means likewise movable in a vertical path, means for automatically moving said two means, and top feed mechanism movable in the line of the work and also up and down relatively to such work and means for automatically moving it.

19. In a sewing machine, the combination of means for folding the edge of one or more plies of material and comprising oscillatory means movable in a vertical path, means for infolding the previously folded edge and comprising means likewise movable in a vertical path, means for automatically moving said two means, said infolding means movable transversely of the work and also in the line of travel of the work, and top feed mechanism movable in the line of the work and also up and down relatively to such work and means for automatically moving it.

20. In a sewing machine, the combination of means for folding the edge of one or more plies of material and comprising oscillatory means movable in a vertical path, means for infolding the previously folded edge and comprising means likewise movable in a vertical path, means for automatically moving said two means, trimming mechanism having a movable blade movable in a horizontal path, top feed mechanism movable in the line of the work and also up and down relatively to such work, and means for automatically moving it.

21. In a sewing machine, the combination of means for folding the edge of one or more plies of material and comprising oscillatory means movable in a vertical path, means for infolding the previously folded edge and comprising means likewise movable in a vertical path, means for automatically moving said two means, trimming mechanism having a movable blade movable

in a horizontal path, top feed mechanism movable in the line of the work and also up and down relatively to such work, and means for automatically moving it, said top feed mechanism movable in the line of the work simultaneously with the movement of the infolding means in the line of the work.

22. In a sewing machine, the combination of means for folding together the edge or edges of one or more plies of material, independent means for infolding the so folded edges and comprising an oscillatory foot movable transversely of the line of travel of the material and also movable with the work, a needle lever, and means connecting said infolding foot with the needle lever.

23. In a sewing machine, the combination of means for folding and gripping or clamping the work, means for infolding the previously folded edge, a needle bar actuating lever, means connecting said needle bar actuating lever with the infolding means, and means connecting said needle bar actuating lever with the gripping means.

24. In a sewing machine, the combination of means for folding and gripping or clamping the work, means for infolding the previously folded edge, a needle bar actuating lever, means connecting said needle bar actuating lever with the infolding means, and means connecting said needle bar actuating lever with the gripping means, the connecting means between the needle bar actuating lever and the gripping means comprising a toggle connection.

25. In a sewing machine, the combination of means for folding and gripping or clamping the work, means for infolding the previously folded edge, a needle bar actuating lever, means connecting said needle bar actuating lever with the infolding means, and means connecting said needle bar actuating lever with the gripping means, the connecting means between the needle bar actuating lever and the gripping means comprising a toggle connection, the gripper connecting means also having means for permitting the same to automatically adjust itself to the thickness of the work.

26. In a sewing machine, the combination of means for folding the edge of the work, a single movable means for further folding such edge laterally and depressing it and also clamping the said folded edge, and means for then infolding the said folded edge.

27. In a sewing machine, the combination of fixed means for folding the edge of the work, a single movable means for further folding such edge laterally and depressing it and also clamping the so folded edge of the work, and movable means for then infolding the said folded edge of the work.

28. In a sewing machine, the combination

- of means for folding the edge of the work, means for trimming the folded edge, a single means for then folding the trimmed edge laterally and depressing it and also 5 clamping the so folded edge, and means for then infolding the said folded edge.
29. In a sewing machine, the combination of means for folding the edge of the work substantially a quarter turn, trimming means 10 for then trimming the edge of the work, and means for then infolding the previously partly folded edge of the work.
30. In a sewing machine, the combination of means for folding the edge of the work 15 substantially a quarter turn, trimming means for then trimming the edge of the work, means for then folding and clamping the previously partly folded portion of the work, and means for then infolding the so 20 folded portion of the work.
31. In a sewing machine, the combination of means for folding a part of the work substantially a quarter turn, trimming means effective to trim the so partly folded portion 25 of the work, means for then manipulating the so partly folded portion of the work for the infolder, and means for then infolding the previously folded portion of the work.
32. In a sewing machine, the combination of fixed means for partly folding the edge 30 of the work, movable means for folding and clamping the previously partly folded portion of the work, movable means for infolding the previously folded portion of the 35 work, and trimming means having a movable blade movable in a horizontal path.
33. In a sewing machine, the combination of movable means for folding the folded edge of material, means for infolding the so 40 folded edge, and trimming means operative to trim the work after the same has been partly folded.
34. In a sewing machine, the combination of fixed means for partly folding the work, 45 means for folding the partly folded work, means for infolding the previously folded portion of work, and trimming means operative to trim the work after the same has been partly folded.
50. 35. In a sewing machine, the combination of means for folding a part of the work, means for folding and clamping the previously partly folded portion of the work, means for infolding the previously folded 55 part of the work, and trimming means operative to trim the work after the same has been partly folded.
36. In a sewing machine, the combination of fixed means for partly folding the edge 60 of the work, movable means for folding and clamping the previously partly folded portion of the work, movable means for infolding the previously folded portion of the work, and trimming means operative to trim 65 the work after the same has been partly folded.
37. In a sewing machine, the combination of means for partly folding the edge of the material, trimming means for then trimming such edge, means for folding the previously trimmed edge, and means for infolding the previously folded edge. 70
38. In a sewing machine, the combination of means for partly folding the edge of the material, trimming means for then trimming such edge, means for folding the previously trimmed edge, means for infolding the previously folded edge, and means for shifting such last two folding means. 75
39. In a sewing machine, the combination of stationary means for upturning the edge of the work, means for trimming such upturned edge, and movable means for infolding such upturned edge. 80
40. In a sewing machine, the combination of stationary means for upturning the edge of the work, means for trimming such upturned edge, movable means for infolding such upturned edge, and means for clamping the edge after it is folded. 85
41. In a sewing machine, the combination of stationary means for upturning the edge of the work, means for trimming such upturned edge, movable means for infolding such upturned edge, and means for clamping the edge after it is folded, said clamping means forming a part of one of said folding means. 90
42. In a sewing machine, the combination of means for upturning the edge of a piece of work substantially a quarter turn, means for then folding the upturned edge of the work, and means for then infolding the previously folded edge. 95
43. In a sewing machine, the combination of means for upturning a piece of work substantially a quarter turn, trimming mechanism having a blade movable in a horizontal path for then trimming the upturned edge of the work, means for manipulating the upturned edge of the work to further fold and clamp the same prior to the infolding thereof, and means for then infolding the so folded edge. 100
44. In a sewing machine, the combination of means for upturning the edge of a piece of work, means for folding the upturned edge of the work, means for infolding the previously folded edge, means for clamping the edge prior to the infolding thereof, 110 and trimming means for trimming the edge after the same has been upturned. 115
45. In a sewing machine, the combination of means for upturning the edge of a piece of work, means for folding the upturned edge of the work, means for infolding the previously folded edge, means for clamping the edge prior to the infolding thereof, 120 and trimming means for trimming the edge after the same has been upturned. 125

trimming means for trimming the edge after the same has been upturned, said trimming means including a blade movable in a horizontal path.

46. In a sewing machine, the combination of means for partly folding the work, movable means for folding the partly folded work, means for limiting the width of the same, and movable means for infolding the 10 previously folded portion of the work.

47. In a sewing machine, the combination of means for partly folding the work, trimming means operative to trim the work after the same has been partly folded, means for 15 folding and clamping the edge of the material, the said folding and clamping means having means for controlling the width of the seam, and means for infolding the so folded edge.

48. In a sewing machine, the combination of means for partly folding the work, trim-

ming means operative to trim the work after the same has been partly folded, means for further manipulating the partly folded work for the infolder, means for limiting 25 the width of the same, and means for infolding the previously folded portion of the work.

49. In a sewing machine, the combination of means for partly folding the work, trimming means operative to trim the work after the same has been partly folded and including a blade movable in a horizontal path, means for folding and clamping the edge 30 of the material, the said folding and clamping means having means for controlling the width of the seam, and means for then infolding the so folded edge.

ROBERT R. HUGHES, JR.
